UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,012, dated April 9, 1889.

Application filed March 7, 1889. Serial No. 302,344. Term of patent 3½ years.

To all whom it may concern:

Be it known that I, JAMES L. FOLSOM, a citizen of the United States, residing in Brooklyn, county of Kings, and State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of a body, A, and a border, B. The body A has a large central group or mass of conventionalized flower and leaf forms. At one side are several large 20 leaf forms with small sprays projecting therefrom. On the other side are a number of smaller leaf forms irregularly disposed. Between these figures, here and there, is an ornamentation producing a watered effect as a

background. The border B has a large figure 25 (shown partly at the right and partly at the left of the photograph) consisting of a circular flower form with radiating scroll forms, and below these a number of large scroll-ended leaf forms. Between these successive 30 figures are smaller serrated leaf forms. There is some intermediate ornamentation producing a watered effect. The outer margin of the border is ornamented with scroll and leaf forms.

What I claim as new, and desire to secure 35 by Letters Patent, is—

1. The design for a carpet, consisting of the body A, substantially as shown.
2. The design for a carpet, consisting of the 40 border B, substantially as shown.
3. The design for a carpet, consisting of the body A and the border B, substantially as shown.

JAS. L. FOLSOM.
